UNITED STATES PATENT OFFICE.

AUSTIN V. M. SPRAGUE, OF NEW YORK, N. Y.

STERILIZING APPARATUS.

SPECIFICATION forming part of Letters Patent No. 671,499, dated April 9, 1901.

Application filed May 23, 1900. Serial No. 17,675. (No model.)

To all whom it may concern:

Be it known that I, AUSTIN V. M. SPRAGUE, a citizen of the United States, residing in the city, county, and State of New York, have 5 invented certain new and useful Improvements in Sterilizing Apparatus; and I do hereby declare the following to be a full, clear, and exact description of the invention, such as will enable others skilled in the art to which 10 it appertains to make and use the same, reference being had to the accompanying drawings, and to characters of reference marked thereon, which form a part of this specification.

15 My invention relates to sterilizing apparatus of the kind employed by physicians and surgeons for the purpose of asepticizing surgical instruments, dressings, and other auxiliaries of the surgical operation.

20 My present invention consists in an improvement upon the apparatus patented to me under United States Letters Patent No. 583,514, granted June 1, 1897.

One of the objects of the invention is to so 25 construct the means for producing a vacuum in said sterilizing-chamber and for admitting the steam for the sterilizing process and to so arrange the same relatively to said chamber as to best conduce to the perfect aseptization of 30 the articles to be treated; and a further object of the invention is to provide for such a disposition of the sterilizing and steam-generating chambers of the apparatus as will afford certain advantages hereinafter clearly 35 indicated.

I have fully illustrated my invention in the accompanying drawings, wherein like characters of reference designate corresponding parts, and wherein—

40 Figure 1 is a longitudinal vertical sectional view of my improved apparatus, certain parts being removed. Fig. 2 is a view in front elevation of said apparatus, certain parts being likewise herein removed; and Fig. 3 is a view 45 in front elevation of a slightly-modified form of my invention.

In said drawings, *a* designates the sterilizing-chamber, said chamber consisting of a thin sheet-metal and seamless shell which is 50 closed at one end and open at the other.

b and *c* are two annular heads. The open-

ing in the head *b*, which is the front one, is disposed eccentrically therein, and the rear face of said head is provided with a flange *d*, surrounding the opening. To this flange is 55 secured, by means of rivets *e*, the outer or open end of the shell *a*, the inner surfaces of the shell and of the head being preferably flush with each other. The flange *d* corresponds in shape to the shape of the head *b*, 60 whose thickness, it will be observed, is greater at the bottom than at the top owing to the eccentric disposition of the opening therein. The head *c* is provided on its face adjacent the head *b* with an annular flange *f*. Riveted 65 to the inner surface of this flange at its rear end and also riveted at its front end to the outer surface of the flange *d* is a cylindrical shell *g*. By preference the rivets *e* are employed to secure both the shell *a* and the front 70 end of the shell *g*.

h is a wall which is secured in place against the outer face of the head *c* by means of studs *i*. This wall is bulged out opposite to the rear end of the shell *a*, so as to leave a 75 clear space between them.

j designates a nipple, which is riveted to the rear wall of the shell *a*, in the lower portion thereof, and which projects through an opening in the wall *h*, in which it rests, thereby acting as a partial support for the rear 80 end of the shell *a*.

k is simply a nut which is screwed onto the nipple and binds against the outer face of the wall *h*. It should be remarked that the 85 nipple is tubular, its bore *l* connecting with an opening *m* in the shell.

n designates a third cylindrical shell, which is secured at its ends about the heads *b* and *c* in any desired manner, said shell having an 90 elongated opening *o* at the bottom. At the top of this shell is disposed a funnel or chimney *p*. The opening *o* is provided in case it is desired to employ a Bunsen burner or other similar heating device, said device being 95 adapted to be disposed beneath this opening, so that the products of combustion can pass up into the shell *n*, both sides of the shell *g*, and out of the chimney *p*. I do not show such a heating device in the drawings, nor is 100 any further reference thereto necessary. The arrangement and construction of this kind of

device suitable for the purposes are clearly shown in my above-mentioned former patent.

5 *g* is a steam-coil, which is disposed in the widened space between the bottom portions of the shells *a* and *g* longitudinally of the apparatus, the same extending through the wall *h*, in the lower portion thereof, and being firmly secured in place by nuts *r* binding against the opposite faces of said wall.

10 *s* designates the door of the apparatus. This door consists of a circular metallic plate whose inner face—that is to say, that portion thereof which is adapted to abut against the outer face of the head *b*—is perfectly plane, 15 so as to effect with said head, when the door is properly clamped, in place a perfectly tight joint. *t* denotes the hinge upon which this door works, said hinge being secured in any desired manner to the head *b*, and *u* is a knob 20 for operating the door. The edge of this door is provided at regular intervals with notches *v*.

25 *w* is a clamping-ring or annulus, which receives the head *b* and which may be turned thereon, said head and ring having a threaded connection *x* between them. The clamping-ring *w* is provided with a series of lugs or projections *y*, which project inwardly from its inner face, overlapping the peripheral outline of the door when the latter is closed.

30 *z* represents handles or grips disposed at diametrically opposite points on the clamping-ring. By grasping said handles, and thereby turning the clamping-ring, the door may be either locked or unlocked, it being observed 35 that by virtue of threaded connection between the head and the clamping-ring an inward or outward movement will be imparted to the clamping-ring as it is turned. In closing the apparatus, therefore, the ring is first set so 40 that the notches *v* in the door will register with the lugs or projections *y* of said ring. Then when the door is closed the ring is given a turn until, as shown in Fig. 1, its lugs bind against the outer face of the door to clamp it 45 against the head *b*. In opening the apparatus the operation is just reversed.

50 In order to make the joint between the door and the head *b* the more perfect, the latter is provided with an elastic sealing-ring *l*, set in its outer face.

I do not claim in this application the closure of the apparatus comprised in the door and its fittings above described. Said closure is duly claimed in another and copending application constituting a division hereof, filed by me July 31, 1900, and bearing the Serial No. 25,421.

As shown in Fig. 3, I have provided means for operating the ring through the medium 60 of a power-multiplying mechanism, which latter might be desirable in case the apparatus is of considerable size. In this case the ring is provided with peripheral gear-teeth 2, and engaging said teeth is the thread 3 of a worm 65 4, which is journaled in lugs 5, that project downwardly from one of the two castings 6,

constituting supports for the apparatus. One end of the worm carries a crank and a handle 7, whereby said worm may be manually operated.

70 8 is a tubular fitting which communicates with an opening 9 in the forward lower portion of the shell *a*, said fitting being riveted to said shell and projecting downwardly through the shells *g* and *n*. A nut 10 is arranged on the exposed end of this fitting and binds against the outer shell *n*. 11 is another tubular fitting which communicates with an opening 12, diametrically opposed to the opening 9 and formed in the shell *g*, said fitting being riveted to the shell and extending upwardly through the outer shell *n*. 13 and 14 are respectively an elbow and T-joint carried by the said fittings. From the elbow and T-joint extend pipes 15 and 16, and connecting the free ends of said pipes is another pipe 17, which terminates slightly below the pipe 15. The pipes 15 and 16 are controlled by valves 18 and 19, respectively, and in the pipe 17, at the junction of the pipe 15 therewith, is disposed an ejector 20. (Shown in dotted lines in Figs. 2 and 3.)

21 is a filling device consisting of a funnel having a cock 22, mounted on the T-joint 14.

23 is a water-gage which has communication at its top and bottom with the interior of the shell *g* through the medium of tubes 24 and fittings 25 and 26, projecting, respectively, upwardly and downwardly from the shell *g*, to which they are riveted, and through the outer shell. The water-gage is provided with valves 25' for controlling its communication with the interior of the shell *g* and with a petcock 26', whereby said water-gage and the shell *g* may be drained. The fitting 25 is in two parts, its upper part carrying a safety-valve 27, a steam-gage 28, and an air-escape valve 29, all of which have communication with the interior of the shell *g*.

30 100 25 is a fitting which forms a valve-casing 110 having connecting-ports 31 and 32, affording communication between the interior of the shell *a* and the space between said shell and the shell *g*, said fitting being riveted to the shell *a* and projecting upwardly through the 115 two outer shells. Connection between the ports 31 and 32 is afforded through the medium of a tubular bore 33 of the fitting, and in this bore is arranged a spindle or valve-stem 34, having a threaded engagement with the fitting and having its lower end tapered and adapted to seat in the port 31, so as to close the same. Secured to the top of the spindle or stem 34 is a disk 35 for turning it 120 so as to seat or unseat the tapered end of said spindle.

125 In dotted lines in Fig. 1 I show a connection secured to the nipple *j* and adapted for the attachment of an air-filtering device, such as is shown and described in my above-mentioned patent.

130 In operation, water being introduced into

the chamber formed by the shell *g* through the funnel 21, and steam being generated in said chamber either by the coil *q* or by other exterior heating means, (the air in the chamber being permitted to escape at the valve 29 meanwhile,) when the desired pressure is attained and the articles to be sterilized have been placed in the chamber formed by the shell *a* and the door closed and clamped 5 tightly in place the valves 18 and 19 are opened, so that steam in discharging from the pipe 17 may draw off the air in the sterilizing-chamber by way of the pipe 15. Steam is then admitted to the sterilizing-chamber through 10 the medium of the fitting 30, by way of the ports 31 32 thereof. When the sterilization has been carried on the proper length of time, the valve-stem 34 is seated again, thereby cutting off the supply of steam to the 15 sterilizing-chamber. It is now necessary to exhaust the steam of sterilization from the shell *a*, and this is effected by again opening the valves 18 and 19, so that the ejector may act. A vacuum being now formed in the 20 sterilizing-chamber and it being necessary to destroy it, so that the door may be opened, air is permitted to enter the chamber through the nipple *j* and the air-filter, to which I have 25 already referred.

25 By disposing the shell *a* eccentrically in the shell *g*, leaving the greatest interval between them at the bottom, not only is it possible to use a much larger size coil *q* than can be employed in the old construction, where the 30 shells are arranged concentrically, but it is very convenient by virtue of the enlarged space at the bottom to clean out the sediment that collects there from time to time, and this 35 operation of cleaning out the shell *g* is rendered very simple, furthermore, because the coil being secured to the back wall both may be removed intact, the said enlarged space being thus left clearly exposed for the unobstructed introduction of the implements for 40 removing the sediment. Another and very material benefit is derived from thus disposing the shells eccentrically the one within the other with the maximum interval of space between them at the bottom. It is a matter 45 of considerable convenience to the operator where the apparatus is frequently used to have to replenish the water-supply as seldom as possible and not be required to waste time waiting for steam to generate. In an 50 apparatus of this nature, it may be here remarked, steam-space can well be made to give way to water-supply space. The peculiar disposition of the cylinders referred to therefore has special value in that it considerably increases 55 the capacity of the water-supply of the apparatus, and not only this, but at the same time the use of a heating-coil proportionate in size to the increased capacity of the water-supply is rendered possible, and so the 60 water can be brought to the steam-generating point with quite as much expedition as formerly, if not more. In other words, by

the simple expedient of disposing the inner shell eccentrically increased water-space and space for an increased size of coil necessary 70 to heat the water so augmented are afforded, while a decrease of steam-space, another item of considerable importance in an apparatus of this nature, is produced.

In my previous patented construction the 75 exhausting was effected from near the top of the sterilizing-chamber and the steam admitted near the bottom. My present apparatus presents an advantage over this arrangement in that the exhausting is done at 80 the extreme bottom of the chamber, while the steam is admitted at the extreme top. As steam is lighter than air, it will be observed that by the new arrangement the exhausting can be made quite complete and perfect. In 85 exhausting the air the steam of sterilization may be admitted a little before the exhaustion is complete, thus acting to crowd the air out at the bottom.

It will be seen that by means of the fitting 90 30 the steam is admitted directly from the generating-chamber to the sterilizing-chamber by a passage arranged entirely within the former, and so it is in its perfect condition for effecting the sterilization when it enters 95 the latter chamber. The steam is thus kept at all times within the bounds of the cylindrical jacket of heat-containing fluid wherein it is produced, being exposed to no external condensing influences whatsoever, it 100 being observed that it is one of the important considerations in sterilization of this kind to maintain the dressings, instruments, &c., under treatment perfectly dry.

Having thus fully described my invention, 105 what I claim as new, and desire to secure by Letters Patent, is—

1. In a sterilizing apparatus, the combination of two substantially cylindrical shells arranged the one within and spaced from the other, the inner shell constituting the sterilizing-chamber and the outer shell constituting a chamber for the generation of steam of sterilization and for the liquid for conversion into such steam, and also for the reception 115 of a heating device, and means for effecting communication between said shells, said shells being disposed eccentrically with the maximum interval of space between them at their bottom or liquid-containing, and the minimum interval of space between them at their 120 top or steam-containing, portions, substantially as described.

2. In a sterilizing apparatus, the combination of an annular head, two substantially 125 cylindrical shells arranged the one within and spaced at all points from the other and each closed at one end and secured at its other end to said head, the inner shell constituting the sterilizing-chamber and the outer shell constituting a chamber for the generation of steam of sterilization and for the liquid for conversion into such steam, and also for the reception of a heating device, means for ef-

- fecting communication between said shells, said shells being disposed eccentrically so as to bring the maximum interval of space between them at their bottom or liquid-containing, and the minimum interval of space between them at their top or steam-containing, portions, and a heating device disposed in said maximum interval of space between said shells, substantially as described.
- 10 3. In a sterilizing apparatus, the combination of two shells arranged the one eccentrically within the other with the maximum interval of space between their lowermost portions, the inner shell constituting the sterilizing-chamber and the outer shell constituting the chamber for the generation of the sterilizing medium, means for effecting communication between said shells, the outer shell being closed at one end, a removable wall for the other end of said outer shell, and a heating device carried by and removable with said wall, said heating device being disposed in said maximum interval of space between said shells, substantially as described.
- 15 4. In a sterilizing apparatus, the combination of two shells arranged the one within and communicative with the other, the inner shell constituting the sterilizing-chamber and the outer shell constituting the chamber for the generation of the sterilizing medium, an annular head, each shell being secured thereto at one end, the end of the inner shell remote from said head being permanently closed, a removable wall for the corresponding end of the outer shell, a nipple projecting from said inner shell and penetrating and resting in said outer shell, and a heating device disposed between said shells, said heating device being carried by and removable with said wall, substantially as described.
- 20 5. In a sterilizing apparatus, the combination of two cylindrical shells arranged the one within the other and the outer one constituting a chamber for the generation of the sterilizing medium and being closed, means for closing the inner shell, means for exhausting said inner shell, and means for effecting communication between the shells, said last-named means comprising passages disposed 25 interiorly of said outer shell, substantially as described.
- 25 6. In a sterilizing apparatus, the combination of two cylindrical shells arranged eccentrically the one within the other with the maximum interval of space between their bottom portions, heads, one of said heads having a flange shaped in conformity to the space between said shells and said shells being secured to said flange at one end, and the outer shell being secured at its other end to the other head, a removable wall secured to said last-named head, a heating device arranged in said maximum interval of space between the shells, the inner shell constituting the sterilizing-chamber and the outer shell constituting a chamber for the generation of the sterilizing medium, and means for effecting

communication between the shells, said means comprising passages disposed interiorly of said outer shell, substantially as described. 70

7. In a sterilizing apparatus, the combination of two cylindrical shells arranged eccentrically the one within the other with the maximum interval of space between their bottom portions, heads, one of said heads having a flange shaped in conformity to the space between said shells and said shells being secured to said flange at one end, and the outer shell being secured at its other end to the other head, a removable wall secured to said last-named head, a closure mechanism for the inner shell, a heating device arranged in said maximum interval of space between the shells, detachably secured to and removable with said wall, the inner shell constituting the sterilizing-chamber and the outer shell constituting a chamber for the generation of the sterilizing medium, and means for effecting communication between the shells, substantially as described. 80 90

8. In a sterilizing apparatus, the combination of two cylindrical shells arranged the one eccentrically within the other with the maximum interval of space between their bottom portions, heads, one head having a flange shaped in conformity to the space between said shells and said shells being secured thereto at one end, and the outer shell being secured at its other end to the other head, a wall removably secured to said last-named head, a tubular nipple communicating with and secured to the inner shell and resting in an opening in said wall, a closure mechanism for the inner shell, means for exhausting said inner shell, a heating device arranged in said maximum interval of space between the shells and detachably secured to said wall, the inner shell constituting the sterilizing-chamber and the outer shell constituting the chamber for the generation of the sterilizing medium, and means for effecting communication between the shells, substantially as described. 95 100 105

9. In a sterilizing apparatus, the combination of two shells arranged the one within the other, the outer shell being closed, means for closing the other shell, means for exhausting the inner shell, said exhausting means communicating with said shell at the bottom thereof, and means for effecting communication between said shells, said last-named means having connection with the interior shell at the upper part thereof, and comprising a passage or passages disposed interiorly of said outer shell, substantially as described. 110 115 120 125

In testimony that I claim the foregoing I have hereunto set my hand this 8th day of January, 1900.

AUSTIN V. M. SPRAGUE.
